UNITED STATES PATENT OFFICE.

JOHN HARRIS, OF NUNEATON, ENGLAND.

COLLAR-SHAPING MACHINE.

Application filed February 14, 1927, Serial No. 168,083, and in Great Britain July 16, 1926.

This invention relates to collar shaping machines and has for its object the provision of an improved device for shaping or rounding the top portion of a double fold 5 collar.

Heretofore, it has been the general practice to employ means, for shaping the collar, which leave the collar too sharp edged and therefore uncomfortable to the neck.

10 Further it has been found that there was a tendency for the tie to be held too tightly within the fold and the object of the present invention is to provide an improved machine for the beforementioned purpose whereby 15 the said disadvantages are avoided and which shapes the collar quickly, with a suitably rounded top edge. Further the device as constructed according to the present invention is cheap to manufacture, economical in use and efficient in action.

In order that my invention may be easily understood I append hereto three sheets of drawings in which:—

Fig. 1 is a perspective view of one form 25 of the device constructed according to the invention.

Fig. 2 is a diagrammatic plan view of the 30 device shown in Fig. 1, showing the gearing and driving means for the spindles and shafts.

Fig. 3 is a detail view showing the 35 resilient means for supporting the spindle carrying the grooved forming wheel.

Fig. 4 is a detail view showing the 40 resiliently supported bearing for the vertical shaft.

In the device as shown in Figs. 1 and 2, a rotating main spindle A (shown in Fig. 2) is arranged beneath a table B, said 45 spindle A being driven by a belt C and wheel D and being controlled by means of a clutch D¹, thrown into or out of engagement by means of a handle D². On the main spindle A, is fixed a chain wheel A¹, which drives by means of a chain A² a second chain wheel, E² fixed to the end of a second spindle E. Spindle E is resiliently supported in a bearing E³, the said bearing being endwise movable against the pressure of a spring E⁴ 50 carried in the bearing housing E⁵ and being adjustable endwise by means of a bolt E⁶ adapted to be secured in adjusted position by a lock nut E⁷. The chain wheels A¹ and E² and the chain A² are housed in a suitable cover F. At the end of the spindle E, 55 towards the centre of the table B, is fixed a

rotating grooved wheel G formed as shown in Fig. 2, so as to shape the top edge of the collar (as indicated in dotted lines by H, Fig. 1). Disposed on the table B beneath the forming grounded wheel G is a rail or support J adapted to receive the collar H and fixed at such a distance that the collar comes into contact with the forming wheel G.

On the main spindle A beneath the table B is a bevel pinion K, which drives a vertical shaft L by means of a bevel wheel K¹, fixed on the said shaft L, said shaft being supported resiliently in bearings M carried 70 in a housing M¹, fixed on the table B. The bearing M is endwise movable against the pressure of a spring M², and is adjustable endwise by means of a bolt M³, acting against the end of the bearing M, said bolt being adapted to be secured in adjusted position by a lock nut M⁴.

The vertical shaft L causes to rotate a rubber roller or rubber faced wheel N fixed on the end of said shaft L in close proximity to the rail or support J, which passes partly around said rubber faced wheel N, as shown in Fig. 2. Arranged outside the said rail J, and passing around said wheel N, close to it is a guard O, carrying vertical rotating rollers O¹.

The grooved wheel G is externally heated by means of a gas flame issuing from a pipe P, fixed to the side of the cover F and curving round to a point to the side of the wheel G, as shown.

In using the machine, the gas issuing from pipe P is ignited and the machine set in motion. The collar H is then pushed over the rail J, and beneath the heated forming wheel G. The rotation of this wheel pushes the collar along the rail J, the collar being shaped at the top edge while being passed beneath the wheel G, and when it comes into contact with the rubber faced wheel N, it is 95 dragged along the rail and around the wheel, its movement being assisted by the vertical rollers O¹ until it is eventually ejected from the machine at the point Q. The operation is then repeated and it has 100 been found that the speed of the work is greatly increased and that the collar will be suitably and uniformly rounded at the desired place.

What I claim is:—

In a collar shaping machine, a rail for supporting a collar, a grooved wheel co-

operating with one edge of said rail to move a collar therealong and to shape the fold of the same, a portion of said rail being curved, a guard, a portion of which extends contiguous with and in spaced relation to the curved portion of said rail, and rollers carried by said guard with which one side of a

collar moving along said rail is adapted to engage to facilitate movement of the collar along said rail.

In witness whereof I have signed this specification.

JOHN HARRIS.
